UNITED STATES PATENT OFFICE.

LAWRENCE F. KENNEDY, OF ST. PAUL, MINNESOTA.

RESILIENT RECOIL-PAD FOR GUN-STOCKS.

1,328,924.

Specification of Letters Patent. Patented Jan. 27, 1920.

Application filed May 8, 1919. Serial No. 295,733.

To all whom it may concern:

Be it known that I, LAWRENCE F. KENNEDY, a citizen of the United States, residing at St. Paul, in the county of Ramsey and State of Minnesota, have invented certain new and useful Improvements in Resilient Recoil-Pads for Gun-Stocks, of which the following is a specification.

My invention relates to resilient recoil pads for gun stocks and an object is to provide a pad of this character which may be easily attached and detached for use on army rifles, machine guns, sporting rifles and shot guns. In the use of guns and rifles, especially such as are employed for army purposes, there is a great deal of recoil, which results in much bruising and injury to the shoulder of the soldier or user, so that frequently the shoulder becomes so sore that it is difficult to aim and fire accurately. A resilient recoil pad for application to the butt of the gun is, therefore, extremely desirable. Such a pad, however, will not bear the rough usage incident to handling and drilling with the gun. My invention provides means whereby a recoil pad may be easily and quickly applied to the gun when the same is to be used for firing the gun, and detached at other times, leaving the usual metallic butt plate exposed.

The full objects and advantages of my invention will appear in connection with the detailed description thereof and the novel features embodied in my inventive idea will be particularly pointed out in the claims.

Referring to the accompanying drawings, which illustrate the application of my invention in one form,

Figure 1 is a side view of the recoil pad attached to the butt of a gun. Fig. 2 is a view in section on the line 2-2 of Fig. 1. Fig. 3 is a rear elevational view of an ordinary butt plate showing how the same may be modified to adapt it to my invention. Fig. 4 is a rear elevational view of another form of butt plate. Fig. 5 is a view in longitudinal section. Fig. 6 is a view in elevation looking at the front side of the recoil pad. Fig. 7 is a view in section on the line 7-7 of Fig. 6.

As shown in the drawings, the end of the gun stock 10 is provided with a metallic butt plate 12. This plate may be an army butt plate as shown in Figs. 3 and 4 in which there is a gate 14 for admission to the thong case chamber, the gate having a notched

finger piece 16 for use in opening the gate. The butt plate 12 is secured to the gun stock by screws 18 and 20, the screw 20 extending through an outstanding arm 22 with which the butt plate is provided. When the gun is being carried or shipped, and when in use for drilling, the butt plate 12 will alone be employed, and this being of metal and closely fitting the end of the gun stock will bear the hard usage of drilling and handling.

The attachment for providing a resilient recoil pad comprises a piece 24 of substantially rigid material such as hard rubber to which is secured a pad member 26 of resilient material such as sponge rubber, the latter being shaped on the rear side to fit the shoulder by concaving it at 27. The pad 26 may be provided with corrugations 28 on its side which is adjacent the member 24, and the latter is formed with a central aperture 30. The pieces 24 and 26 are covered with leather 32 and to the forward side of the piece 24, near one end thereof, is secured a metallic plate 34 carrying an outstanding stud 36 having an elongated head which is adapted to coöperate with an elongated slot 38 provided for this purpose in the butt plate. To the other end of the piece 24 is secured an outstanding metallic arm 40 containing an opening or recess 42 adapted to coöperate with a projection such as the head of the screw 20 on the gun stock. When the recoil pad is in the position shown in Fig. 2 the head of the stud 36 may be readily inserted through the elongated slot 38, whereupon by turning the pad member the latter will be held upon the gun stock. When the pad member reaches an upright position the opening or recess 42 will be engaged by the head of the screw 20 or other projection on the gun stock, and the pad will be held firmly in place since the arm 40 is slightly resilient.

It will be apparent that the recoil pad member may be quickly and easily attached to and detached from the butt of the gun by turning the member through substantially ninety degrees, and that when attached it merely completes the butt for firing purposes and when detached leaves the butt in the normal condition for carrying and drilling. The butt plate of any rifle or gun may easily be fitted for the application of my recoil pad attachment by simply drilling the elongated slot in the butt plate. The

recoil pad attachment also permits the use of any form of door for opening through the butt plate into a chamber or chambers formed in the body of the gun stock. My 5 resilient recoil pad is compact and may be easily carried in a coat pocket or a compartment of the cartridge belt. Some of the advantages of my device may be summed up as follows:

- 10 1. It positively eliminates the shock of the recoil.
2. It increases the efficiency of the marksman.
3. It does away with flinching.
- 15 4. It eliminates sore or bruised shoulders.
5. It conduces to accurate aim.
6. It fits the shoulder with absolute comfort.

I claim:

- 20 1. A resilient recoil pad for gun stocks comprising a member of resilient material for engagement with the shoulder, a stud carried by said member, said stud having an elongated head for coöperation with an

elongated slot in the butt plate whereby said 25 member may be attached and detached by turning the same through substantially ninety degrees, and an arm extending forwardly from said member, said arm being adapted for resilient action with the gun 30 stock.

2. A resilient recoil pad for gun stocks comprising a member of substantially rigid material, a member of yielding material secured to said rigid member, a stud carried 35 by said rigid member, said stud having an elongated head for coöperation with an elongated slot in the butt plate whereby said members may be attached and detached by turning the same through substantially 40 ninety degrees, and an arm extending forwardly from said rigid member, said arm having a recess for engagement by a projection on the gun stock.

In testimony whereof I hereunto affix my 45 signature.

LAWRENCE F. KENNEDY.
